FRED W. WILLIAMS, OF SANTA MARIA, CALIFORNIA.

MULTIPLE FUSE PLUG.

Application filed January 9, 1926. Serial No. 80,257.

This invention relates to improvements in fuse plugs, and it consists of the constructions, combinations and arrangements herein described and claimed.

5 An object of the invention is to provide a fuse plug having a plurality of fuses which can be successively introduced into the electrical circuit as preceding ones are melted or burned out, thereby obviating the necessity of making a replacement with an entirely new plug each time a fuse wire is burned, a further purpose of the invention being to construct the plug with such simplicity that it can be manufactured very 10 cheaply.

Other objects and advantages appear in the following specification, reference being had to the accompanying drawing, in which

15 Figure 1 is a central longitudinal section of a fuse plug constructed in accordance with the invention.

Figure 2 is a detail cross section taken substantially on the line 2—2 of Figure 1.

20 Figure 3 is a plan view of the plug. Figure 4 is an inverted perspective view of the revoluble insulating disk.

Figure 5 is a cross section taken on the line 5—5 of Figure 1.

25 In carrying out the invention provision is made of a porcelain or other insulating base 1 to the small end of which the customary metallic shell 2 is suitably affixed. This shell is stamped into the shape of screw threads so that the plugs can be screwed into a complementary receptacle in the fuse box. The shell 2 has electrical connection with the side contact 3. This contact terminates in a head 4 and a tortuously bent end 5 which functions as a spring.

30 The center contact 6 is appropriately fixed in the base 1, and extends a short distance above the surface of the larger end of the base. An insulating disk 7 of rubber, fiber or other suitable material, has a central hole 8 which receives the head 9 of the center contact and permits engagement of said head with the center of the fusible element or spider 10.

35 The insulating disk 7 is revoluble in respect to the base 1, and for this purpose provision is made of a brass or other metallic cap 11 which at 12 is bent over the edge of the mica disk 13, holding the disk in place

upon the insulating disk 7, and at 14 is bent under the edge of the base 1 in order to 55 retain the cap. However, the cap is sufficiently loose at 14 to permit manual revolution or turning of the insulating disk and its carried parts in reference to the base 1, side contact 3 and center contact 6. The brass cap 11 is also crimped at 15 (Figs. 3 and 5) to tightly hold the cap in place at the edge of the disk.

40 Particular reference is made to the fusible element 10. This element resembles the hub and spokes of a wheel. The arms 16 thereof radiate from the common center which makes engagement with the head 9 of the center contact 6. The insulating disk 7 is depressed at 17 in the formation thereof, providing a recess or pocket at the bottom of which the element 10 is firmly lodged. The shape of the depression 17 will agree exactly with the shape of the element 10, and by looking down upon the multiple fuse 75 plug and through the mica window 13 (Fig. 3) the observer sees the depression 17 and the fusible element 10 at the bottom of the depression.

45 The arms 16 of the fusible element are reduced or constricted at 18 but immediately broadened at 19 to produce what might be called heads. These heads have a definite purpose. The constriction 18 may be varied to suit the amperage of the fuse plug. In 50 other words, a fuse plug designed to carry six amperes of current will be narrower at the constriction 18 than one designed to carry ten amperes.

55 As to the purpose of the heads 19: The insulating disk 7 has non-circular openings 20 (Figs. 4 and 5) at the outer extremities of the depressions 17. The head 4 of the side contact 3 occupies these openings in succession, as the cap 11 is turned to introduce new 55 fuse arms into the circuit. One of the radial edges of each opening is beveled at 21 providing an approach over which the contact head 4 can readily move when the cap 11 is turned to displace the head 4 from the 60 respective openings 20. Presuming a particular fuse arm 16 to be mounted at the constriction 18. It is apparent that there would be some possibility of the free or broken end 65 dropping down into the respective opening 20 to conflict with and probably impair the 100 105

freedom of action of the spring 5 and the rotation of the cap 11. However, the heads 19 are broader than the openings and thereby rest on each side of the openings, preventing the foregoing contingency.

6 A pointer or indicator 22 marks the position of the contactor head 4. This pointer registers with the head 4 in the radial direction, and by observing the indicator 22 the 10 user of the plug can ascertain the position of the contactor head and turn the cap 11 accordingly.

15 The operation of the fuse plug is readily understood. The reader will remember that the insulating disk 7 has a depression 17 of the shape of the fusible element 10. This element is shaped like the spokes and hub of a wheel, and the depression 17 agrees therewith. The fusible element is firmly lodged 20 at the bottom of the depression, and it is visible from the top of the fuse plug.

25 The head 4 of the side contact 3 enters the openings 20 from beneath, and makes contact with the fusible element on the underside of the heads 19. The engagement of the head 4 with the heads 19 is successive, and occurs each time that the cap 11 is turned sufficiently far in the right direction. The tortuously bent end 5 of the side contact imparts the necessary resiliency to the head 4, causing the latter to snap into the successive opening and make good contact with the exposed end of the fusible element.

30 The engagement of the head 9 of the center contact 6 and of the head 4 with the underside of the fusible element 10 furnish the support of the insulating disk 7 in spaced relationship with the large end of the base 1. The head 9 of the center contact fur- 35 nishes a bearing upon which the cap 11 is turned. The electrical circuit is completed from the threaded shell 2 to the center contact 6 to the side contact 3 and that one of the arms 16 of the fusible element 10 that 40 happens to be in registering position.

45 Upon melting of that arm at the constriction 18 the electrical circuit will of course be opened, but the user can turn the cap 11 until the next arm is brought into operation. The fragment of the former arm will however, not drop through the respective opening 20 because it is made sufficiently broad to overlap the edges of the opening (see Figs. 2 and 5) and will therefore re- 50 tain its position.

55 While the construction and arrangement of the improved multiple plug is that of a generally preferred form, obviously modifications and changes may be made without

departing from the spirit of the invention 60 or the scope of the claims.

I claim:—

1. A fuse plug comprising a base, center and side contacts carried by the base, a fusible element having a plurality of radial arms, an insulating disk having a depression on top corresponding with the shape of the fusible element at the bottom of which depression the fusible element is firmly lodged, said disk having a central opening at which the center contact makes engagement with the element in the center, a plurality of openings at which the substantial extremities of the arms are exposed at the underside and at which the side contact makes engagement therewith; a transparent pane through which the entire depression and element are visible, and means both clamping the pane upon the insulating disk and providing a rotatable mounting for the disk upon the base 80 permitting turning of the disk to cause successive engagement of the side contact with the respective arms, and indicator means stationarily mounted upon the base coinciding in radial position with the side 85 contact.

2. A fuse plug comprising a base, center and side contacts carried by the base, a fusible element having a plurality of radial arms, an insulating support for said ele- 90 ment having openings exposing the element on the underside respectively for permanent engagement of the center contact and for successive engagement of the side contact with each of the arms, and a bent formation 95 incorporated in the end of the side contact increasing its resiliency so that it functions as a spring.

3. A fuse plug comprising a base, center and side contacts carried by the base, a fusible element having a plurality of radial arms, an insulating support for said element having openings exposing the element on the underside respectively for permanent en- 100 gagement of the center contact and for successive engagement of the side contact with each of the arms, a bent formation incorporated in the end of the side contact 105 increasing its resiliency so that it functions as a spring, means rotatably mounting the insulating support upon the base, and bevels cut at one of the radial edges of each of the arm openings permitting depression of the spring end of the side contact and disengagement thereof from the respective opening 110 when turning said support for engagement of the spring end with the next arm.
